United States Patent Office.

JOHN GOODIN, OF CENTRALIA, ILLINOIS.

Letters Patent No. 89,575, dated May 4, 1869.

IMPROVEMENT IN WRENCHES.

The Schedule referred to in these Letters Patent and making part of the same.

To all whom it may concern:

Be it known that I, JOHN GOODIN, of Centralia, in the county of Marion, and in the State of Illinois, have invented certain new and useful Improvements in Wrenches; and do hereby declare that the following is a full, clear, and exact description thereof, referring being had to the accompanying drawings, and to the letters of reference marked thereon.

The nature of my invention consists in the construction and arrangement of a wrench, in which the jaws separate and approach each other on a line at right angles with the handle, instead of parallel with the same, as is usually the case.

In order to enable others skilled in the art to which my invention appertains, to make and use the same, I will now proceed to describe its construction and operation, referring to the annexed drawings, which form a part of this specification, and in which—

Figure 1 is a side view of the wrench;

Figure 2, an edge view of the same;

Figure 3, a side view of the movable jaw; and

Figure 4, a side view of the stationary jaw.

A represents the handle of the wrench, which at one end is cut and bevelled, so that nails can be drawn with the same.

At the other end the handle A spreads, forming the flat, broad portion B, at the end of which, on one side, the stationary jaw C is formed.

On the same side as the jaw C, but near the base of the flat portion B, is a raised surface, a, on which a dog, b, is pivoted, the inner end of said dog, or pawl being pressed inward by a spring, c, secured to a flange, d, rising from near the base of the flat portion B.

Along the opposite side of the flat portion B, is a raised flange, e, the object of which will be hereinafter set forth.

Across the flat portion B, between the raised surface a and the flange e, is an elongated slot, f, rounded at both ends, as shown in fig. 4.

The under side of the flat portion B is grooved to receive the slide D, at one end of which is formed the jaw E.

The groove on the under side of the flat portion B extending across the same, enables the slide D to be moved from one side to the other, thus causing the movable jaw E to separate from or approach to the stationary jaw C on a line at right angles with the handle A, instead of parallel, as is usually the case.

A cam-wheel, F, which is provided on one side with notches i i, is pivoted by means of a screw, G, which passes through the slot f in the flat portion B, and into the slide D, thus at the same time holding said slide in its position in the groove on the under side.

By turning the cam-wheel F, its outer edge presses against the flange e, which causes the slide D, jaw E, and the cam-wheel also to move closer to the stationary jaw C, and the dog, or pawl b being pressed against, or in the notches i i, holds the movable jaw in any position desired.

To separate the jaws, it is only necessary to raise the pawl d out of the notch, when the cam-wheel can be turned in the opposite direction, which causes the slide D and jaw E to move away from the stationary jaw C.

Having thus fully described my invention,

What I claim as new, and desire to secure by Letters Patent, is—

1. The arrangement of the handle A, having a flat, broad portion, B, which is slotted and grooved as described, the stationary jaw C, raised surface a, pawl b, spring c, and flanges d and e, all substantially as shown and described.

2. In combination with the handle A, flat portion B, and stationary jaw C, the slide D, movable jaw E, and notched cam-wheel F, all constructed and operating substantially as and for the purposes herein set forth.

In testimony that I claim the foregoing, I have hereunto set my hand, this 1st day of February, 1869.

JOHN GOODIN.
